Edward R. Alexander

Attorney.

UNITED STATES PATENT OFFICE.

EDGAR H. WEIL, OF CLEVELAND, OHIO, ASSIGNOR TO THE VITREOUS ENAMELING COMPANY, OF CLEVELAND, OHIO, A CORPORATION OF OHIO.

TRAY.

1,319,195.

Specification of Letters Patent. Patented Oct. 21, 1919.

Application filed May 19, 1919. Serial No. 298,311.

To all whom it may concern:

Be it known that I, EDGAR H. WEIL, a citizen of the United States, residing at Cleveland, in the county of Cuyahoga and 5 State of Ohio, have invented certain new and useful Improvements in and Relating to Trays, of which the following is a specification.

My invention relates to apparatus for 10 drying various materials, including pigments, dye-stuffs, chemicals, explosives and glue, and particularly to the trays for such apparatus.

One object of the invention is to provide 15 a metallic tray having a perforated bottom whereby treatment of chemicals and materials may be effected economically and uniformly.

Another object of the invention is to provide 20 a metallic tray having a perforated enameled bottom whereby the chemicals and materials are economically and uniformly treated and at the same time prevented from contacting with the metal of the tray.

Another object of the invention is to provide 25 a metallic drying tray having a bottom formed with a plurality of openings the walls of which extend downwardly below the plane of the bottom to prevent contact of the material on the tray with the peripheral edges of the openings.

A further object of the invention is to provide 30 an enameled drying tray formed with a plurality of openings whose walls extend downwardly below the plane of the tray to position the free peripheral edge of such openings out of contact with the materials placed on the tray.

Other objects of the invention will be 35 apparent to those skilled in the art to which my invention relates from the following description taken in connection with the accompanying drawing.

For the purpose of illustration, I have, in 40 the accompanying drawing shown and herein described one form of apparatus embodying my invention.

Figure 1, is a top plan view of a tray, 45 embodying my invention, a portion of tray being broken away.

Fig. 2, is a section of the line 2—2 of Fig. 1.

Fig. 3, is the elevation of one end of the 50 tray looking in the direction of the arrows 3—3.

Fig. 4, is a fragmentary view enlarged taken on line 2—2 of Fig. 1.

Fig. 5, is a fragmentary view of a slightly modified tray having a larger number of openings than the tray shown in Fig. 1. 60

In the drawings, 1 indicates as an entirety a tray having a bottom 1^a. The tray may be and preferably is provided with one or more side walls 1^b the upper edges of which may be rolled over to strengthen the 65 side walls and the tray as an entirety and avoid the formation of rough edges. For sake of economy and convenience, the bottom 1^a and side walls 1^b are formed from a single metallic sheet of suitable shape and thickness, which is bent in any well known manner to form the side walls and rolled edges. The tray may be of any desired size and shape. 70

2 indicates a plurality of openings formed 75 in the bottom 1^a. The openings 2 may be of any desired shape and size, and there may be a larger or smaller number of openings 2, depending upon the character and nature of the materials to be supported on 80 the tray for drying or treatment. Furthermore, the openings 2 may be arranged in any order desired; they are preferably uniformly separated from each other between the opposite edges or side walls 1^b in order 85 that uniform drying or treatment may be effected in the most efficient manner. The metal constituting the walls of each opening 2 is bent downwardly and inwardly or toward the center of opening, as shown at 90 2^a, so as to dispose the free peripheral edge 2^b of the opening below the plane of the bottom 1^a.

3 indicates a suitable coating for the upper surfaces of the bottom 1^a and walls 95 2^a of the openings 2. The coating 3 is formed of a chemical resisting material, preferably vitreous enamel. The purpose of the enamel coat is to prevent contact of the chemical materials with the metal constituting the walls of the tray and particularly 100 the tray bottom on which the material is placed.

While it is only necessary, in carrying out 105 my invention, to enamel the upper surface of the tray bottom, it is quite advantageous for many reasons to enamel the entire tray by dipping it in a bath and thereafter baking it. As I prefer this form of construction, I have, in the accompanying drawing illus- 110

trated a tray which has been enameled in this way. As shown, the coat 3 covers all surfaces of the bottom 1^a, walls 2^a and side walls 1^b. The coat 3 therefore not only prevents contact of the chemical materials with the metal from which the tray is formed, but also protects such metal from the heat and other elements used for or in connection with the treatment or drying of the materials on the tray.

The tray embodying my invention is particularly adapted for use in drying apparatuses of the character in which the trays are removably supported in superposed series, one above the other and spaced from each other to permit the circulation of the drying medium above and below each tray. As all surfaces of the tray are enameled, it is well adapted for various types of drying apparatus including those in which moisture or vapor is used to facilitate drying.

Heretofore, it has not been possible to use metal trays and particularly metal trays having perforated bottoms because the metal or ingredients therein would affect the chemical materials in various ways, chemically and otherwise, depending upon the nature and character of the materials being treated. I have discovered that metal trays can be advantageously used by enameling, with vitreous enamel, the surface of the tray bottoms and hence prevent contact of the chemicals with the metal of which the tray bottoms are constructed.

It is well known, in enameling metal plates and metallic articles, that exposed free edges of the metal cannot, practically or commercially, be enameled completely so as to entirely and permanently cover such edges. Accordingly, in carrying out my invention, I countersink the openings 2 in the tray bottom; that is, I bend or curve the metal constituting the walls of each opening downwardly and inwardly, as shown at 2^a, so that the free edge or peripheral edge of the metal, which may be more or less exposed, is entirely below the plane of the tray bottom and therefore is out of contact with the materials being treated on the tray.

An enameled metallic tray embodying my invention has several important advantages,

among which may be mentioned, to-wit, cheapness of construction, durability, elimination of repairs and rusting, and fire-resisting characteristics. In connection with this last-mentioned advantage, attention may be called to the fact that many chemical plants in operation today are equipped with apparatus all of which are made of fire-proof materials except the drying trays; by using my invention in such plants, all equipment therein can be made entirely fire-proof.

In carrying out my invention I use a tray provided with metallic perforated bottom which enables me to secure in an economical and efficient manner treatment of the materials, particularly where heat or heat and moisture is or are used for drying purposes. By providing the bottom with suitable sized openings, equally spaced from each other, the treatment is effected uniformly and quickly. From the foregoing description it will be seen that by enameling the tray bottom and countersinking the perforations thereof, I am enabled to produce a very cheap, but durable tray of fire-proof material and at the same time adequately prevent contact of the material with the metal constituting the wall or walls of the tray.

To those skilled in the art of making apparatus of the class described, many alterations in construction and widely differing embodiments and applications of my invention will suggest themselves, without departing from the spirit and scope thereof. My disclosures and description herein are purely illustrative and are not intended to be in any sense limiting.

What I claim is:

An article of manufacture comprising a metallic tray having an enameled bottom on which chemicals and other materials are adapted to be disposed, said bottom being formed with a plurality of relatively small openings the walls of which are bent downwardly to dispose the free or exposed edge of the metal below the plane of said bottom.

In testimony whereof I affix my signature.

EDGAR H. WEIL.

Witness:

GEORGE H. HAYS.
